UNITED STATES PATENT OFFICE.

NORMAN ROSS TAIT, OF WHATATUTU, NEW ZEALAND.

PEN-NIB-EJECTING MEANS.

Application filed July 16, 1928, Serial No. 293,073, and in New Zealand May 8, 1928.

This invention relates to improved means for use in combination with an ordinary pen nib holder whereby the nib may be ejected from the holder in an easy manner and without any handling of the nib itself.

The means designed are of such a nature as to be adapted to engage the nib slot while the nib is in its holder and when the device has been slipped over the holder, so that when it is moved outward on the holder it will push the nib with it. The said device may be allowed to remain on the holder when the pen is in use but may also be slipped on to it for the nib ejecting operation, whenever needed, if so desired.

The invention is illustrated in the accompanying drawings, in which:—

Figure 1 is a side elevation of the ejector.

Figure 2 is a side elevation of a pen, showing the ejector, in section, in position thereon ready to eject the pen nib.

Figure 3 is a plan thereof.

The ejector device comprises a sleeve A of such a diameter as to be capable of sliding on to the nib holder B of the pen, passing also over the nib C inserted in such holder. Combined with this sleeve is a spring tongue D that is fastened to one end of the sleeve so that it extends for a distance in the longitudinal line of the sleeve. This tongue is given a natural downward tension at its free end. Such free end also is bent downward and is flattened out as at E to adapt it to pass into the slot F of the nib C and its flattened

end E is preferably made with a shoulder e. 35

In the use of this ejector device, the sleeve is slid over the nib and on to the nib holder, the tongue D extending forwardly so that its bent down end E slides over the nib top until it comes to the slot F thereof. Then 40 because of the inherent springiness of the tongue, the end E springs down into the slot, so that when the sleeve is pushed forwardly on the nib holder, the tongue end E engages the slot end and pushes the nib out 45 of the holder. The shoulder e in this engagement locks beneath the slot end to prevent any liability of the tongue springing out of the slot when pressure is placed upon the sleeve. 50

If desired, a finger grip G may be secured to the back end of the sleeve A to enable the sleeve to be actuated in sliding it upon the nib holder.

I claim:—

1. Pen nib ejecting means comprising a sleeve adapted to slide upon a pen nib holder, and a spring tongue projecting from the forward end of such sleeve having its forward end bent down and flattened to adapt it for 60 passing into the pen nib slot, substantially as specified.

2. In pen nib ejecting means according to claim 1, a finger grip attached to the said sleeve, substantially as specified. 65

In testimony whereof, I affix my signature.

NORMAN ROSS TAIT.
